UNITED STATES PATENT OFFICE.

HARRY WASHINGTON WATSON, OF MEMPHIS, TENNESSEE.

DRILL HOLDING AND RELEASING DEVICE.

Application filed January 26, 1922. Serial No. 531,968.

To all whom it may concern:

Be it known that I, HARRY W. WATSON, a citizen of the United States, and a resident of Memphis, in the county of Shelby and State of Tennessee, have invented certain new and useful Improvements in Drill Holding and Releasing Devices, of which the following is a specification.

My present invention relates generally to 10 drill holders, and more particularly to what are commonly known as drill sockets, having tapering bores for the reception of the stem of a drill, which are usually provided also with transverse slots providing for the 15 use of a drift and hammer in releasing the drill from the socket.

It is a well known fact that considerable time is wasted at the present time in removing drills with a drift and hammer, occasioned by the fact that in many instances both the drift and hammer are not closely 20 at hand, and it is also well known that a great deal of loss is occasioned by injury to the drill or socket, occasioning trouble 25 in the use of the taper.

It is also a well known fact that considerable loss is occasioned by the fact that when drifted out of its socket, the drill quite frequently falls and is either broken 30 or at least injured to the extent that regrinding is made necessary.

It is the primary object of my invention to provide a drill holding and releasing device, through manual manipulation of 35 which a drill may be readily and easily released, as well as one wherein this release may be accomplished with one hand only, leaving the other hand entirely free to grasp the drill itself and hold the same 40 when released.

In the accompanying drawing which illustrates my present invention and forms a part of this specification,

Figure 1 is a side view, partly broken 45 away and in section, showing the drill socket with a drill therein ready for use.

Figure 2 is a side view, partly broken away and in section, of the drill socket, the view being taken at right angles with respect to Figure 1, and

Figure 3 is a detail perspective view showing the drill engaging members and their support.

Referring now to these figures my invention proposes a drill socket 10 having the usual lower cylindrical portion 11 bored on

a taper as at 12 corresponding to the taper of the stem 13 of a drill 14 shown in Figure 1, and provided at the inner end of the lower cylindrical portion 11, with a transverse slot 15, through which in the absence of other parts the usual drift might be hammered into engagement with the inner tang 16 of the drill stem for the purpose of dislodging the latter from the bore of the 65 socket.

In accordance with my present invention however the external surface of the socket 10 is threaded as at 17 for the length of the slot 15 at least and on this threaded portion an internally threaded sleeve 18 works to control a pair of drill engaging and releasing members 19, whose inner slightly overlapping ends are engaged by the inner end of the tang 16 of a drill when the latter is properly within the socket, and whose outer ends project through the slots 15 and into the upper counterbore 19 of the sleeve 18, said counterbore forming an annular shoulder 20 at its lower end within the sleeve 80 adapted to engage the outwardly projecting ends of members 19.

My invention also contemplates the use of a pivotal connection for the drill engaging and releasing members 19, in the nature of 85 a cross bar 21 which is extended through the slots 15 at the inner ends of the latter and is provided with a pair of rounded bearing members 22 projecting therefrom upon opposite sides of the axis of the socket, said 90 bearing members being extended into conformable grooves 23 of the members 19 and thus constituting fulcrums upon which the members 19 are adapted to move in performing their functions as drill releasing 95 dogs.

The cross bar 21 is prevented from rotation by virtue of the extension of its ends into the slots 15 of the socket, and is confined against lengthwise displacement diametrically of the socket by virtue of its housing within the sleeve 18, and it is thus obvious that with the two releasing dogs 19 in the normal diametrically alined relation as shown in Figure 1, a drill such as the drill 105 14 may be properly shifted into the socket for use.

It is also obvious however that upon rotation of the sleeve 18 in one direction, the bearing which this sleeve has against the 110 outer ends of the dogs 19 by virtue of its internal shoulder 20, will cause rocking of

the dogs on their fulcrum bearings 22 so that the inner ends of the dogs will be forced downwardly against the drill tang 16 in order to force the drill stem 13 downwardly to a sufficient extent so that the latter may be detached and withdrawn by hand.

It is still further obvious that in this operation the sleeve 18 may be turned by one hand while the other hand is left free to grasp the drill 14 and remove the latter without danger of falling and becoming marred or otherwise injured. For the purpose it is preferable in practice that the external surface of the sleeve 18 be milled or otherwise roughened and it is probable that diametrically opposite openings 24, or an annular series of such openings may be provided in the external surface of the sleeve for the introduction of a pin or other implement to assist in the rotation of the sleeve.

I claim:

1. A drill socket having a drill receiving bore and transverse slots at the inner end of its bore, and external threads adjacent to said slots, a sleeve having internal threads engaging the threads of the socket and having a counterbore at one end forming an internal shoulder, a cross pin extending through the slots of the socket with its ends projecting into the counterbore of the sleeve and held against lengthwise displacement by the latter, said cross pin having rounded bearing members within the bore of the socket upon opposite sides of the axis of the bore, and a pair of dogs fulcrumed on said bearing members within the bore of the socket, having inner overlapping drill engaging ends and having outer ends projecting through the slots of the socket and engageable and shiftable by the inner annular shoulder of the sleeve.

2. A drill socket having a drill receiving bore and lengthwise slotted diametrically op-

posed openings at the inner end of the bore, a pair of dogs fulcrumed intermediate their ends within the bore and having their outer ends projecting externally through said slotted openings, and means movable upon the external surface of the socket for engaging the said outer ends of the dogs to actuate the latter, and a support for the fulcrums of said dogs in the nature of a cross pin also extending through the slotted openings of the socket.

3. A drill socket having a drill receiving bore and lengthwise slotted diametrically opposed openings at the inner end of the bore, a pair of dogs fulcrumed intermediate their ends within the bore and having their outer ends projecting externally through said slotted openings, and means movable upon the external surface of the socket for engaging the said outer ends of the dogs to actuate the latter, and a support for the fulcrums of said dogs in the nature of a cross pin also extending through the slotted openings of the socket, said dog actuating means being in the form of a sleeve, threaded upon the external surface of the socket and a portion of which houses the said cross pin to prevent lengthwise displacement of the latter and the said dogs.

4. A drill socket having a bore and transversely disposed lengthwise slotted openings in opposed relation at the inner end of the bore, a supporting member extending through the slots at their inner ends, a pair of dogs having bearings on the said support forming fulcrums for the dogs and normally extending at right angles to the longitudinal axis of the socket with their outer ends projecting through the said slots, and a member movable upon the exterior of the socket having means to engage the outwardly projecting ends of the dogs for shifting the latter on their fulcrums.

HARRY WASHINGTON WATSON.
